RICHARD DUDGEON, OF NEW YORK, N. Y.

Letters Patent No. 61,815, dated February 5, 1867.

IMPROVED APPARATUS FOR EXPANDING AND FASTENING BOILER TUBES.

The Schedule referred to in these Letters Patent and making part of the same.

TO ALL WHOM IT MAY CONCERN:

Be it known that I, RICHARD DUDGEON, of the city, county, and State of New York, have invented a new and useful Roller-Expanding Tool for expanding the ends of boiler tubes, and that the following is a full, clear, and exact description of the same, reference being had to the accompanying drawings, in which—

Figure 1 represents an elevation of a roller-expanding tool embodying my invention.

Figure 2 represents an end view of the same.

Figure 3 represents a central longitudinal section of the same.

Figure 4 represents a cross-section of the same at the line $x-x$ of fig. 3.

Figure 5 represents a cross-section of the same at the line $y-y$ of fig. 3.

Figure 6 represents an elevation of another one of the modes in which I have contemplated the application of the principle of my invention.

Figure 7 represents a cross-section thereof at the line $x-x$ of fig. 6; and

Figures 8 and 9 represent rollers of differing profiles.

The object of the invention is to enable the ends of boiler tubes to be expanded in the holes in the flue sheet. Previous to this invention it has been customary to expand the ends of tubes by an expanding-tool, composed substantially of a series of swages radiating from a common centre, and caused to diverge by means of a tapering plug driven into the centre of the tool by the repeated blows of a maul or sledge. The principle of the invention which constitutes the subject-matter of this patent is to expand the tube by rolling the metal by the application of one or more pressure-rollers to the interior of the tube, so that the metal is extended by rolling, in contradistinction to the old system of driving it outwards by hammering; and as the roller can be operated by hand, the use of mauls or sledges, and all the inconveniences that attend their employment, are dispensed with.

My invention may be embodied in various forms; that which I prefer for practical use is represented in figs. 1, 2, 3, 4, and 5. In this example three rollers, $a a a$, are held in a stock, B, and are operated by means of a tapering plug, C, inserted between them. The rollers should be set at equal distances apart; they should also be of equal size, and their profiles should be the same as that of a longitudinal section of the interior of the extremity of a tube when properly expanded. Their journals c are also held in radial slots, which permit the rollers to move outwards from the centre of the stock. In this case the tapering plug is simultaneously forced inwards between the rollers and turned upon its axis by the application of the hands of the operator to a wrench or spanner, D, fitted to the head of the plug C; and the rollers are caused to turn by the frictional contact of the surface of the plug with their surfaces, so that the series of rollers are caused to roll within the end of the tube, and are at the same time caused to diverge by the turning and entrance of the tapering plug. Moreover, as the tapering plug and roller-stock are free, or not attached to each other, the plug may be turned at a different speed from that at which the roller-stock revolves, and the rollers bear at one side of these barrels against the tube, and at the other against the tapering plug, so as to act as true rollers between the surfaces of the two. The slots which hold the journals of the rollers may be slightly skewed so that the axes of the rollers will be slightly skewed to the axes of the tube, the effect of which arrangement is to cause the tapering plug, when turned, to be drawn into the tube, and to thus expand the rollers; or the tapering plug may have a shallow flat screw-thread formed upon its surface, so that it will draw itself inwards as it is turned by hand. But neither the slightly skewed arrangement of the rollers nor the thread is essential to the successful operation of the instrument. In order to hold the rollers in their innermost positions when the tool is inserted into the tube I have formed a ring-groove in the stock B, and have inserted in it a spring-ring, g, to bear upon the journals of the rollers and hold them in their inner-positions when the tapering plug is withdrawn. In order that one tool may be used for performing the two operations of expanding the tube and of trimming off its end the expanding-rollers and stock are combined with a cutter, E, which is arranged to turn upon the stock B of the expanding-rollers, so that the compound tool thus formed may be used first to expand the tube and then (by turning the cutter E without withdrawing the tool) to trim off the end of the tube. In this case the rollers retain their positions in the groove which they have formed by rolling, and hold the tool in the tube while the cutter is operating. The cutter may be turned by a wrench or by a ratchet-handle, G, operating in a manner

similar to the handle of a ratchet-drill; and the cutter may be forced against the tube by the action of a nut, H, fitted upon a screw which is formed upon the outer end of the roller-stock B.

Although I prefer the above-described mode of embodying my invention, the most important part of it may be embodied in tools of other forms, one of which is represented at figs. 6 and 7. In this tool the rollers *a a a* are supported upon arbors *c c c* in a ring frame or stock, B, which is inserted in the end of the tube to be expanded. The rollers are arranged to turn loosely upon the arbors, so that they may be caused to diverge by the action of the tapering plug C, which is inserted between them, and is simultaneously pushed into the ring frame and turned by the application of a wrench to its head, f. The profiles of the rollers are the same as the profile of the interior of the expanded end of the tube, and the surface of the tapering plug C has a shallow screw-thread formed upon it, so that the turning of the plug causes it to draw itself in between the rollers. In the roller-expanding tools represented in the drawings I have represented rollers with profiles adapted to expand the tube in the form commonly produced by the old expanding tools; but I prefer to use rollers such as are represented at figs. 8 or 9, with profiles, either straight, or straight with a shallow indentation, forming a ring groove around the roller, the effect of which is to form a slight bead within the tube, which bead holds the tool in its place after the work is commenced. When such rollers are used the hole in the tube-sheet may be left cylindrical without the edges being chamfered or countersunk. The expanding-tool may be used in connection with a gauge to fix its position by bearing upon the tube-sheet at the sides of the tube so that the rollers will be set at the places where the tubes are to be expanded, however the projection of the end of the tubes beyond the tube-sheet may vary. Although I prefer a tapering or wedge-formed plug as the expanding instrument, I do not limit my invention to an expanding instrument of that form, as circumstances may render expedient the use of an expanding instrument of different form.

In all the above-described modifications of the roller-expanding tool at least one roller is combined with a tapering plug (or its equivalent, by whose action the roller is forced outwards in the tube,) and with a stock or holder, which is not attached to the tapering plug, and by which the roller is prevented from twisting sidewise as it is turned round in the tube, and the freedom of the tapering plug (which is the expanding-instrument) is important because the roller is thereby permitted to act as a true roller between the expanding-instrument and the tube, and the expanding-instrument may be turned in the tube at a speed different from that at which the roller is carried around. The main feature of my invention, therefore, consists of the combination of at least one roller with a roller-stock and an expanding-instrument that is free, or not so attached to the roller-stock that the two must turn simultaneously; but the cutter and ratchet-handle constitute useful combinations which are supplementary to the aforesaid fundamental combination.

What, therefore, I claim as my invention, and desire to secure by Letters Patent, is—

The combination in an expanding-tool of the following herein-described implements, viz: the roller, roller-stock, and free-expanding instrument, these three operating in combination substantially as set forth.

I also claim the combination in an expanding-tool of the following implements, viz: the roller, roller-stock, expanding-instrument, and cutter for trimming the tube, all operating in combination substantially as set forth.

I also claim the combination in an expanding-tool of the following implements, viz: the roller, roller-stock, cutter, and a ratchet-handle for turning it, all operating in combination substantially as set forth.

I also claim the combination in an expanding-tool of the following implements, viz: the roller, roller-stock, cutter, and screw-feed therefor, all operating in combination substantially as set forth.

In testimony whereof I have hereunto set my hand this fifth day of March, A. D. 1868.

RICHARD DUDGEON.
